UNITED STATES PATENT OFFICE.

WILLIAM F. LANGE, OF ELGIN, ILLINOIS, ASSIGNOR TO WALTER F. ACKEMANN, OF ELGIN, ILLINOIS.

SPARK-PLUG.

1,354,617.

Specification of Letters Patent.

Patented Oct. 5, 1920.

Application filed July 24, 1919. Serial No. 312,967.

To all whom it may concern:

Be it known that I, WILLIAM F. LANGE, a citizen of the United States, residing at Elgin, in the county of Kane and State of Illinois, have invented new and useful Improvements in Spark-Plugs, of which the following is a full, clear, and exact description.

My present invention relates to improvements in spark plugs, and has for its objects the provision of a spark plug which will protect both the sparking terminals and the porcelain, or other insulation employed, from the heat developed from the combustion of the air and fuel in the chamber of the cylinder, and also will protect the insulation from the high pressure resulting from and concomitant with the aforesaid combustion. The exclusion of the high temperature from the ignition chamber not only protects the insulation from deterioration on account of such high temperature, but, also, operates to maintain the current carrying sparking terminals at a lower and more uniform temperature which insures a uniform conductivity and operation of these elements. Other objects of my invention are, first, the provision of an accurately working structure in which the back pressure into the ignition chamber from the main cylinder chamber will be dependably excluded, and, second, the provision of a structure in which the igniting gases leaving the ignition chamber will be so directed as to wipe and clean the seating portion of the valve which I employ. It will also be hereinafter seen that my device secures a wide distribution of the ignited and flaming gases from the ignition chamber to the main chamber of the cylinder, thereby facilitating the ignition of the charge in the cylinder, and a further accomplishment of my spark plug is to fully protect the surfaces of the insulation, as well as the sparking terminals from an accumulation of lubricant, and also largely from the deposition of carbon by means of excluding from the ignition chamber the products of combustion taking place within the main cylinder or piston chamber. It will also be seen that if the insulation or the sparking terminals should break, or otherwise come adrift, they will be retained within the ignition chamber and prevented

from falling into the main cylinder or piston chamber where they might possibly cause 55 damage.

I attain the aforesaid objects by means of the structure illustrated in the accompanying drawings, in which—

Figure 1 is an elevation of a spark plug 60 embodying my invention.

Fig. 2 is a central longitudinal section thereof.

Fig. 3 is a central section through the ignition chamber of the plug showing how 65 the structure may economically be built integrally with the plug instead of being assembled therewith.

Fig. 4 is a fragmental central section of a modified manner of constructing and assembling the structure shown in Figs. 1 and 2.

Throughout the several views of the drawings, I have employed the same reference characters for indicating similar parts. 75

It is believed that my invention may be installed in a great many of the plugs at present on the market, so that the plug itself, herein shown, is merely schematic. Such schematic plug consists of an outer 80 casing 4, exteriorly threaded, at 5, and, preferably, slightly tapered to screw into the cylinder wall of an internal combustion engine. Above the threaded portion, the casing is, preferably, enlarged, at 6, and hexagonally formed to receive a wrench for properly screwing the aforementioned outer casing into the cylinder wall. 85

The bore of the casing is enlarged to form a shoulder 7 upon which seats an annular 90 rib or extension 8 provided upon the insulating core 9. The upper enlarged portion of the casing being internally threaded, at 10, to assemble with a hollow retaining nut 11, which engages with the annular extension 8 95 of the insulating core, and for more perfectly sealing this construction, I have shown a copper gasket 12 between the upper edge of the casing 4 and the under surface of the laterally extended upper portion of 100 nut 11. The insulating core is provided with a central bore to receive the conductor rod 13, the lower portion of which is enlarged, at 14, to prevent its withdrawal upwardly through the bore in the insulating 105 core, and is secured in proper position by

means of the nut 15 coöperating with the exteriorly threaded upper end of the conductor rod. Above the nut 15 is a binding nut 16 by means of which a circuit wire can 5 be secured in electrical connection with conductor rod 13. Below the enlargement 14, the conductor rod is extended to form a sparking terminal 17 which coöperates with a rod 18 seated in and extending from the 10 inner wall of outer casing 4 to form sparking terminals.

For the purpose of providing an ignition chamber, a hollow cylindrical member 19 is inserted and secured in any suitable manner 15 into the lower end of the bore of casing 4. This cylindrical member 19 is transversely bored to provide the diametrically oppositely positioned pin sockets 20. Slidingly fitted within member 19 is the hollow tube 22, the 20 lower end of which is closed by a disk-like portion 23, the edge whereof extends beyond the outer face of tube 22, and is proportioned so that the upper extended surface of the disk will seat upon the lower edge of the 25 wall of the member 19. Tube 22 is longitudinally slotted, at 24, to receive the ends of the pins 25 seated in the pin sockets 20, and the tube 22 is laterally bored just above the disk 23 to provide the preferably, equally 30 spaced ports 26, the slots 24 being so proportioned that the tube 22 will fall by gravity and by pressure created by the initial combustion in the ignition chamber to uncover ports 26.

35 The operation of my device is as follows: Upon the suction stroke of the engine, and at the initial portion of the compression stroke before pressure is developed in the cylinder, there being no pressure upon 40 the disk 23 of tube 22 and tube 22 being in its lowermost position with ports 26 uncovered, a combustible mixture of air and fuel will enter ports 26 and surround the sparking points. Upon the development of pressure in the main chamber of the cylinder, tube 22 and disk 23 will be forced upwardly thereby closing the ignition chamber about the sparking terminals from the main chamber of the cylinder. Upon sparking, the explosive mixture confined within the ignition chamber will be ignited, and the force developed will force down tube 22 and disk 23 until the ports 26 will open when the burning ignited gases will be forced into the explosive mixture in the main chamber of the 55 cylinder. Upon the ignition of the charge contained in the main chamber of the cylinder sufficient pressure will be developed to force tube 22 and disk 23 upwardly seating 60 disk 23 upon the lower edge of the wall of member 19, and at the same time close ports 26 in tube 22, thereby excluding from the ignition chamber the pressure, the heat and the products of combustion created by the 65 ignition of the relatively large amount of

fuel contained in the main chamber of the cylinder.

It will be seen that the mere upward movement of tube 22 will close ports 26, but that in addition to this closure, I doubly 70 secure the exclusion of the pressure, heat and exploded gases from the ignition chamber by means of the seating of the disk 23 upon the lower edge of the walls of member 19. It will also be seen that tube 22 functions as a valve stem for disk 23, and that the relatively large diameter of tube 22 secures its easy and dependable working within member 19 without the necessity of more than ordinary nicety of construction, and 80 that the rubbing of the outer surface of tube 22 against the inner surface of member 19 will keep their respective surfaces free from the adherence or accumulation of any products of combustion. 85

It will be further seen that ports 26 open directly between the lower end of member 19 and the upper surface of disk 23 and that the discharge of the ignited gases from these ports will tend to clean these surfaces, and it will also be noted that the location of the extended portion of disk 23 adjacent the ports 26 will cause the spreading of the ignited gases leaving the ports so as to cause their wider distribution in the main chamber of 95 the cylinder.

In the modified construction, shown in Fig. 3, instead of providing a separate member 19 to form a downwardly opening passageway for the ignition chamber, I have 100 shown the walls of the outer casing 4 provided with an integral extension 19^a to perform the functions of the separate member 19. Otherwise the constructions are the same. 105

In the modified construction, shown in Fig. 4, the downwardly opening passageway of the outer casing 4^a is interiorly threaded to receive the exteriorly threaded hollow cylindrical member 19^a. In this form of construction sparking terminals 27 are seated in the walls of member 19^a, and by screwing member 19^a farther in or farther out an adjustment between the sparking points 27 and the central terminal 13 may 110 be made. I have shown two oppositely arranged sparking points 27; but one such point, or more than two may be employed without departing from the spirit of my invention. 115

With the form of construction, shown in Fig. 4, a somewhat longer sliding hollow tube 22^a is threaded to receive an annular nut 28, by the adjustment of which the latitude of the movement of tube 22^a in member 19^a may be adjusted. The lower end of tube 22^a is closed with a disk 23^a in all respects similar to disk 23, and tube 22^a is also provided with ports 26^a, similar in position, and operation to ports 26. The tube 22^a is, 120 125 130

of course, longitudinally slotted, at 29, 29, to accommodate the terminals 27 projecting from the inner wall of member 19^a.

Having described my invention, what I claim as new and desire to secure by Letters Patent is—

1. In a spark plug, a hollow cylindrical member adapted to be secured to the lower end thereof, a tube vertically reciprocable therein, means for limiting the reciprocation of said tube, a disk closing the lower end of said tube extended to seat upon the lower edge of said cylindrical member when said tube is in its upper position; said tube being provided with ports adapted to be uncovered in the lowermost position thereof.

2. In a spark plug, a chamber surrounding the sparking terminals thereof and having an extension forming a downwardly opening cylindrical passageway, a tube extending into said chamber and reciprocable within said passageway, a closure for the lower end of said tube adapted to seat upon

the lower end of the wall of said cylindrical passageway when said tube is in its upper position; said tube being provided with radial ports located to be uncovered in the lowermost position thereof.

3. In a spark plug, a chamber surrounding the sparking terminals thereof and having a downwardly opening cylindrical passageway, a tube extending into said chamber and reciprocable within said passageway, a closure for the lower end of said tube, means carried by said tube adapted to seat upon the lower end of the wall of said cylindrical passageway when said tube is in its upper position; said tube being provided with ports located to be uncovered in the lowermost position thereof.

Signed at Elgin, county of Kane and State of Illinois, this 21st day of July, 1919.

WILLIAM F. LANGE.
